DESIGN FOR A CASING FOR A FRUIT MIXER

Monroe Harrison, Chicago, Ill.

Application November 16, 1936, Serial No. 65,920

Term of patent 14 years

To all whom it may concern:

Be it known that I, Monroe Harrison, a citizen of the United States, residing at Chicago, in the county of Cook and State of Illinois, have invented a new, original, and ornamental Design for a Casing for a Fruit Mixer, of which the following is a specification, reference being had to the accompanying drawing, forming a part thereof.

In the drawing:

The figure is a side elevational view of the casing for a fruit mixer showing my design.

The contour of the casing is circular in horizontal cross section, throughout.

I claim:

The ornamental design for a casing for a fruit mixer substantially as shown and described.

MONROE HARRISON.
